(57) **CLAIM**

The ornamental design for gas meter, as shown and described.

DESCRIPTION

FIG. 1 is a perspective view for gas meter;

FIG. 2 is a front view of the design for gas meter as seen in FIG. 1;

FIG. 3 is a top view of the design for gas meter as seen in FIG. 1;

FIG. 4 is a back view of the design for gas meter as seen in FIG. 1;

FIG. 5 is a bottom view of the design for gas meter as seen in FIG. 1;

FIG. 6 is a right view for gas meter;

FIG. 7 is a left view of the design for gas meter as seen in FIG. 6;

FIG. 8 is a perspective view of the design for gas meter as seen in FIG. 6;

FIG. 9 is a front view of the design for gas meter as seen in FIG. 6;

FIG. 10 is a top view of the design for gas meter as seen in FIG. 6;

FIG. 11 is a back view for gas meter;

FIG. 12 is a bottom view of the design for gas meter as seen in FIG. 11;

FIG. 13 is a right view of the design for gas meter as seen in FIG. 11; and,

FIG. 14 is a left view of the design for gas meter as seen in FIG. 11.
